CLEANING DEVICE AND ADAPTOR MEANS
THEREFOR

Elmer C. Morris, Chicago, Ill.

Application March 24, 1945, Serial No. 584,693

6 Claims. (CL. 306—13)

1

This invention relates to cleaning devices and particularly to brushes of the type comprising an elongated brush head mounted on the end of a handle at right angles to the handle in convenient position for use for cleaning floors. It is the object of my invention to improve devices of this type so as to make them more adaptable for use for cleaning out corners, along walls, about the legs of chairs, around table legs or other articles of furniture, or back of fixtures spaced a short distance from walls, and to provide improved devices constructed from metal, interchangeable from old to new brushes, flexible in movement, easy to operate and greatly increase the life of brushes.

For attaining my object, I have provided a pivotal connection between the handle and the brush head or other cleaning member, together with yielding means adapted normally to hold the cleaning member in a predetermined operative position with respect to the handle, but adapted to yield upon the application of pressure thereon for permitting the cleaning member to move to a changed angular position with respect to the handle, and adapted to return the cleaning device again to its normal operative position when released after displacement from such normal position.

It is another object of my invention to provide a device of this type so arranged as to be adapted for use in connection either with a new cleaning device designed for such use or with an old cleaning device. For this purpose, I have provided a conversion or adapter unit comprising a plug adapted to be screwed into the handle opening of a cleaning device, with a socket member pivotally connected therewith and adapted to receive the end of the brush handle, the control spring and other control parts being mounted in cooperative relation to each other on said unit.

It is one of the objects of my invention to provide a new and improved arrangement of control means for holding the cleaning device in the desired angular position with respect to the handle, such improved means comprising preferably a spring-pressed roller or other follower movably mounted on one of the pivotally connected parts in position to have operative engagement with a cam plate mounted rigidly in position with respect to the other of said pivotally connected parts and shaped so as to cause the follower to be displaced against the action of the spring when the cleaning device is moved angularly from its normal operative position, the arrangement preferably being such as to cause the brush head or

other cleaning device automatically to return to its normal angular position when released after having been swung out of such normal position.

It is another object of my invention to improve cleaning devices and adapter means therefor in sundry details hereinafter pointed out. The preferred means by which I have accomplished my objects are illustrated in the accompanying drawing, in which

10 Fig. 1 is a face view of a brush embodying the preferred form of my invention, being partially broken away for clearness of illustration.

Fig. 2 is an end view of the brush shown in Fig. 1.

15 Fig. 3 is a view similar to Fig. 1 but showing a changed position of the brush head with respect to the handle.

Fig. 4 is a longitudinal sectional view through my improved structure by which the handle of a brush is pivotally connected with the brush head.

20 Fig. 5 is a face view of the cam plate forming a part of my improved structure; and

Fig. 6 is a face view of the follower member which cooperates with the cam plate.

25 Referring now to the several figures of the drawing, in which corresponding parts are indicated by the same reference characters, 10 indicates a cleaning or wiper member which in the arrangement shown is in the form of an elongated brush head of the type employed for sweeping floors and the like. As is clearly shown in Fig. 1, the brush head 10 is provided in its face with a screw-threaded socket 11, into which the correspondingly threaded end portion of a wooden handle 12 is adapted to be screwed.

30 For attaining the several objects of my invention in connection with either old brushes or new ones, I have provided an adapter device comprising a screw-threaded plug member which can be inserted into the socket of the brush head in lieu of the usual handle, and comprising a cooperating member pivotally connected with the plug member and provided with a socket into which the handle can be screwed. By the use of such adapter device, an old brush having a handle rigidly connected with the brush head can be quickly and easily converted into the improved type of brush, in which the brush head is pivotally connected with the handle, it being only necessary to transfer the handle from one screw-threaded socket to another and to screw the plug member of the adapter into the socket of the brush head.

35 40 45 50 55 My improved adapter as illustrated comprises

a plug member 13 having external screw threads thereon for removable connection with the socket 11 of the brush head 10 and having a mounting block 14 on its outer end portion and extending between the arms 15 of a bifurcated sleeve 16, such arms 15 being pivotally connected with said block by means of a pivot pin 17. As is shown in Fig. 4, the outer end portion of the sleeve 16 is provided with internal screw-threads for receiving the threaded end of the handle 12 removably therein, the arrangement being such that when the parts are connected as shown in Fig. 1 the handle 12 is adapted to swing into changed angular position with respect to the brush head, being adapted preferably to swing in either direction to the extreme angular position as shown in Fig. 3 with the handle extending longitudinally of the brush head.

The means for holding the handle and the brush head yieldingly in position at right angles to each other comprises a cam plate 18, having a notch 19 in its edge adapted to fit over the block 14 of the plug member so as to engage the face of the brush head when the parts are in their fully assembled condition as shown in Figs. 1 and 2. In its opposite edge, the plate 18 is provided with a rounded notch 20 which is normally engaged by a follower or contact member carried by the sleeve 16. In the arrangement shown, the follower is in the form of a roller 21 rotatably mounted in the end of a slide block 22 which is movable back and forth along the sleeve 16, being normally pressed toward the cam plate 18 by a coiled spring 23 interposed in the sleeve between the slide block 22 and the handle 12. The spring pressure on the slide block 22 and roller 21 serves normally to hold the cam plate 18 in its fully lowered position on the block 14, in the normal assembled position as shown in Figs. 1 and 4.

The block 22 in the arrangement shown is provided with a duct 22a therethrough for the application of lubricant to the roller. The arms at opposite sides of the block 22, between which the roller 21 is mounted, extend downwardly beyond the lower face of the roller into position to engage the opposite faces of the cam plate 18 for holding the block and the roller from rotation about the longitudinal axis of the handle.

The arrangement of the parts is such that when 50 the follower roller 21 is in engagement with the rounded notch 20 in the plate 18 the handle 12 is positioned at right angles with respect to the brush head 10. The notch 20 is of such depth that the pressure of the spring 23 on the follower 55 roller 21 has a substantial tendency to hold the brush head 10 from swinging away from its normal right angled position with respect to the handle 12. When however there is a substantial excess of pressure on one end portion of the brush head as compared with that at the other end portion, the roller 21 is forced by a camming action out of the notch 20 against the action of the spring 23 so as to permit the brush head to swing out of its normal right angular position with respect to the handle. The cam plate 18 is of substantially greater length than width and its shape is such that the roller 21 is forced farther and farther away from the pivot pin 17 as the brush head is swung in either direction away from its 70 normal right angled position with respect to the handle, with the result that the pressure of the spring on the roller is increased more and more as such swinging movement of the head occurs. This arrangement of the spring 23 between bear-

ings on the pivotally connected brush head and handle insures that the spring 23 by its pressure on the roller 21 shall serve to return the brush head to its normal right angled position as soon as the brush head is released after being swung from such normal position.

In the use of my improved cleaning device, the spring 23 serves effectively for holding the brush head normally in its right angled position with respect to the handle so that the device can be used to advantage in its ordinary well-known manner. When, however, one end of the brush head is brought into engagement with an obstruction, such as a wall or the legs of tables or the like, the excess pressure on that end portion of the head causes the head to swing to the necessary extent for permitting the head to slide longitudinally along the obstruction. The strength of the spring 23 and the shape of the cam plate 18 are such that as soon as the brush head passes out of engagement with the obstruction the brush head promptly returns to its normal right-angled position.

By the use of this improved arrangement, the 25 user is able to clean around the legs of furniture, in corners, about and around radiators, and underneath low-set or closely spaced machinery or the like with greatly decreased difficulty and increased speed as compared with that in connection 30 with the use of a cleaning device in which the long brush head is rigid with respect to the handle. The danger of breaking the handle of the device is also very substantially reduced when cleaning in shops or factories, since a sharp 35 blow on one end of the brush head results merely in a swinging movement of the brush head without any weakening effect on any part of the structure.

While I prefer to employ the form of device as 40 shown in my drawing, and as above described, the invention is not to be limited thereto except so far as the claims may be so limited, it being understood that changes might well be made in the form and arrangement of the parts without departing from the spirit of the invention.

I claim:

1. In a cleaning device, the combination of an elongated brush member, a cam plate of greater length than width removably mounted on said brush member so as to be held rigidly in edgewise position thereon with the plate extending longitudinally of the brush head, a handle pivotally connected with said brush head so as to be adapted to swing with respect to said head, a contact member movably carried by said handle in position to engage the edge of the plate, and a spring carried by said handle pressing said contact member forcibly against the edge of said plate for causing said contact member by its pressure on the plate normally to hold the handle relatively in position at right angles to said brush head and adapted to return the handle to such right angled position when released after being moved from such position.

2. In a cleaning device, the combination of a wiper element, a handle pivotally connected with said wiper element, and means for returning the wiper element to position at right angles to the handle when released after being moved from such position, comprising a follower carried by one of said parts and pressed yieldingly by a spring against a cam carried by the other of said parts and arranged so that the pressure of the spring on the follower and cam is increased progressively as the wiper element is swung away

from its right-angled position with respect to the handle.

3. In a cleaning device, the combination of a wiper element, a mounting block removably mounted on the face of said wiper element, a handle pivotally mounted on said block, a plate in the form of a cam having notched engagement with said block, and a spring pressed follower carried by said handle adapted by engagement with the cam surface of said plate normally to hold the plate in position on the block, said cam plate being of substantially greater length than width and being arranged longitudinally of the wiper element so that the follower is moved progressively farther against the action of the spring as the wiper element is moved away from its normal position at right angles to the handle.

4. An adapter for providing a pivotal connection between the brush head and the handle of a cleaning device, comprising adapter members arranged for connection with said brush head and said handle respectively and pivotally connected together so as to enable the handle to swing sideways in either direction away from an intermediate position at right angles to the brush head, and means carried by said members comprising a spring interposed between bearings arranged on said members respectively in spaced relation to the connecting pivot so as to cause the spring to be stressed by relative movement of said members away from said intermediate right-angled position with respect to each other and adapted by such stressed condition normally to return said members to said intermediate right-angled position when released.

5. In a cleaning device, the combination of a wiper member, a handle member to which said wiper member is pivotally connected as to be adapted to have a swinging movement with respect thereto, an arc-shaped cam mounted on one of said members with the distance of the face from the pivot point of the handle increasing progressively from an intermediate point on the cam, a follower movably mounted on the other of

said members in position to engage the face of the cam at said intermediate points thereon when the wiper member stands in a predetermined normal position with respect to the handle, and spring means for pressing said follower against said cam whereby as the handle is swung in either direction for carrying the follower away from said intermediate point on the cam an increasing pressure is applied through the follower to the spring for returning the wiper member to said normal position when released.

6. In a cleaning device, the combination of an elongated brush member, a plug member removably mounted on the face of said brush member so as to project therefrom, a handle pivotally connected with said plug member, a plate in the form of an arc-shaped cam having a notch in its inner face edge engaging said block and extending outwardly from the brush member with the distance of the cam face from the pivot point of the handle increasing progressively from an intermediate point on the cam face, a follower slidably mounted on said handle in position to engage the face of the cam at said intermediate point thereon when the brush member stands in a predetermined normal position with respect to the handle, and spring means for pressing said follower against said cam whereby as the handle is swung in either direction for carrying the follower away from said intermediate point on the cam an increasing pressure is applied through the follower to the spring for returning the brush member to said normal position when released.
